CLAIM

The ornamental design for a cartomizer for an electronic vaping device, as shown and described.

DESCRIPTION

FIG. 1 is a front perspective view of the cartomizer for an electronic vaping device;

FIG. 2 is a rear view of the cartomizer for an electronic vaping device;

FIG. 3 is a front view of the cartomizer for an electronic vaping device;

FIG. 4 is a side view of the cartomizer for an electronic vaping device; and,

FIG. 5 is a rear perspective view of the cartomizer for an electronic vaping device.

In the drawings, the broken lines depict environmental subject matter only and form no part of the claimed design.
